UNITED STATES PATENT OFFICE.

LEWIS PIRDUN AND JOSEPH P. BURKE, OF SAND SPRINGS, OKLAHOMA.

DRIVING AND CONTROLLING THE OPERATION OF REELS.

1,388,885.

Specification of Letters Patent. Patented Aug. 30, 1921.

Application filed November 24, 1920. Serial No. 426,151.

To all whom it may concern:

Be it known that we, LEWIS PIRDUN and JOSEPH P. BURKE, citizens of the United States, and residents of Sand Springs, in 5 the county of Tulsa and State of Oklahoma, have invented certain new and useful Improvements in Driving and Controlling the Operation of Reels; and we do hereby declare the following to be a full, clear, and 10 exact description of the invention, such as will enable others skilled in the art to which it appertains to make and use the same.

This invention relates to improvements in means for driving and controlling the operation of reels, and more particularly to 15 such as are applicable for use with drilling rigs in operating the bailer in oil, gas or water drilling, but which may be employed for other purposes where it is desirable to 20 accurately and economically operate and control a winding reel.

The object of the invention is to provide 25 mechanism of the character specified in which a reel, such as a sand-reel, shall be driven by belting rather than by friction as heretofore proposed, so that the amount of power necessary to drive the reel shall be reduced to a minimum; so that the life of the band wheel shall be prolonged; to eliminate 30 the disadvantages of a friction drive and thereby decrease the amount of vibration of the rig; so that the reel may be driven at a high rate of speed, and so that the cost of upkeep of mechanism of the character 35 to which the invention relates, shall be reduced to a minimum.

With these and other objects in view, the invention consists in certain novel features of construction and combinations of parts 40 as hereinafter set forth and pointed out in the claims.

In the accompanying drawings; Figure 1 is a plan view of mechanism showing an embodiment of our invention; Fig. 2 is a 45 view in elevation; Fig. 3 is an enlarged view partly in section showing the sand reel and parts associated with the shaft thereof; Fig. 4 is a view in section on the line 4—4 of Fig. 3, and Fig. 5 is a view showing 50 the brake.

While our improvements are adaptable for various purposes, we have shown and will describe the same as employed to operate and control a sand reel to operate the 55 bailer for well drilling.

1 represents framework such as employed

in well drilling apparatus and on this framework, suitable bearings are provided for the shaft 2 of a large belt or band wheel 3, said shaft also carrying tug wheels 4. 60

Near one end of the framework, a shaft 5 is mounted in suitable bearings and carries a sand-reel 6 to receive the line or cable of a bailer (not shown), and on this shaft, a pulley 7 is loosely mounted and adapted 65 to be connected to rotate therewith by means of a suitable clutch indicated at 8. The shaft 5 also carries a brake wheel 9, over which a brake band 10 passes,—one end of said brake band being secured to one of the 70 frame timbers and attached at the other end to a crank 11 of a shaft 12 mounted in suitable bearings on the framework.

A belt 13 passes over the large wheel 3 on the shaft 2 and the smaller sand-reel 75 pulley 7 on the shaft 5 and serves to transmit motion from said large wheel to the pulley 7 for driving the sand reel. The large belt wheel 3 is driven by a belt 14 receiving motion from an engine pulley 15 80 and passing over the belt wheel 3 in contact with the belt 13 thereon, and thus the sand reel will be driven by belt gearing and the objectionable features incident to the use of friction driving means heretofore employed will be obviated.

A belt-tightener 16 is provided for the belt 13 which drives the sand-reel, and the arms of this belt-tightener are secured to the 90 crank-shaft 12.

A bracket 17 is located near one end of the framework and provides a support for a lever 18, the latter being pivotally connected above its lower end to said bracket as indicated at 19. The short arm 20 of this lever 95 is connected by links 21 with an arm 22 on the crank shaft 12, so that when said lever is moved, the belt tightener and brake band will be operated. The lever 18 is also connected, by a link 23, with one arm of a bell-crank lever 24, the other arm of which is bifurcated and engages the clutch for shifting the same.

The upper portion of the lever 18 is connected by means of a pitman 25 with a crank 105 shaft 26 located near the other end of the framework, and this shaft is provided with a hand lever 27.

When the hand lever 27 is in the position shown in full lines in Fig. 2, the belt tightener will be released, the clutch 8 disengaged and the brake 9—10 set, and the sand-

reel will be held by the brake and thus be prevented from unwinding.

In order to cause the sand-reel to wind the cable thereon, the operator will shift the hand lever 27 to the dotted line position shown in Fig. 2; whereupon the brake will be released, the clutch engaged with the pulley 7 and the belt-tightener moved to tighten the belt 13. Motion will now be imparted 10 to the sand-reel to wind the cable. When the reel is used for running the bailer in well drilling, the operation will be as follows: The bailer being in the bottom of the hole, the operator will move the lever 27 to 15 the dotted line position shown in Fig. 2 and thus throw the reel into operation as previously explained, to lift the bailer out of the hole. The operator will then move the lever 27 to "neutral" position, viz., half way 20 between the two positions shown (in Fig. 2), thus releasing the brake and belt tightener and setting the clutch in neutral position and thus permitting the bailer to unwind the cable by its own weight.

We have found the apparatus herein described to be decidedly easier to handle and runs more smoothly than in the case of friction driven reels; that vibration to the rig is reduced to a minimum, and that it is 30 economical in the use of power.

Various slight changes might be made in the details of our invention without departing from the spirit thereof or limiting its scope and hence we do not wish to restrict 35 ourselves to the precise details herein set forth.

Having fully described our invention what we claim as new and desire to secure by Letters-Patent, is:—

40 1. The combination with a reel, a pulley for rotating the same, a belt wheel, and means for driving the latter, of a belt passing over said belt wheel and pulley, a belt

tightener for said belt, a clutch for operatively connecting said pulley with the reel 45 and disconnecting it therefrom, and a brake for said reel, of manually operable controlling means common to said belt-tightener, clutch and brake.

2. The combination with a shaft, a reel 50 thereon, a pulley loose on said shaft, a belt wheel, and a belt passing over said belt wheel and pulley, of a clutch for connecting said pulley to the shaft, a belt-tightener for said belt, a brake wheel on the shaft, and a 55 brake band to engage said brake wheel, of a lever pivoted between its ends, connections between one arm of said lever and said belt-tightener and brake band, connections between the other arm of said lever and the clutch, and means whereby said lever may be 60 manually operated to actuate the clutch, belt-tightener and brake band.

3. The combination with a shaft, a reel 65 thereon, a pulley loose on said shaft, a clutch for connecting the pulley with the shaft, a belt wheel, a belt passing over said belt wheel and pulley, a brake wheel on the shaft, and a brake band on said brake wheel and 70 fixed at one end, of a crank shaft having its crank connected with the other end of the brake band, a belt-tightener for said belt connected with said crank shaft, an arm on said crank shaft, a pivoted lever, a connection between said pivoted lever and said 75 arm, connections between said pivoted lever and clutch, and means whereby said lever may be manually operated.

In testimony whereof, we have signed this specification in the presence of two subscribing witnesses.

L. PIRDUN.
J. P. BURKE.
